UNITED STATES PATENT OFFICE

164,545

POWER-DRIVEN WHEEL CHAIR

Sidney E. Beach, Detroit, Mich.

Application September 17, 1949, Serial No. 5,050

Term of patent 3½ years

(Cl. D15—1)

To all whom it may concern:

Be it known that I, Sidney E. Beach, a citizen of the United States, residing in Detroit, county of Wayne, State of Michigan, have invented a new, original, and ornamental Design for a Power-Driven Wheel Chair, of which the following is a specification, reference being made to the accompanying drawings, forming a part hereof.

Fig. 1 is a front perspective view of a power-driven wheel chair embodying my new design.

Fig. 2 is a rear perspective view thereof.

The characteristic features of my design reside in those portions shown in full lines in the drawing.

I claim:

The ornamental design for a power-driven wheel chair, as shown and described.

SIDNEY E. BEACH.
